UNITED STATES PATENT OFFICE.

ANDREW BERG, OF BRIDGEPORT, CONNECTICUT, ASSIGNOR TO THE COULTER & MCKENZIE MACHINE COMPANY, OF BRIDGEPORT, CONNECTICUT.

WIRE-CHAIN-MAKING MACHINE.

Application filed February 4, 1922. Serial No. 534,027.

To all whom it may concern:

Be it known that I, ANDREW BERG, a citizen of the United States, residing at Bridgeport, in the county of Fairfield and State of Connecticut, have invented certain new and useful Improvements in Wire-Chain-Making Machines; and I do hereby declare the following to be a full, clear, and exact description of the invention, such as will enable others skilled in the art to which it appertains to make and use the same.

This invention relates to chain making machines, and is particularly adapted for making and interlocking short links, being an improvement on my former patent dated December 12, 1922, No. 1,428,474. In the present construction I employ a two part former or mandrel, one part being stationary and the other part movable, the link being formed about the two parts when closed together, and when a link is formed, the mandrel is separated, while the link carrying jaws are tilted to strip the new formed link from the stationary part of the mandrel and carry it into position where a new link is interlocked at one side of its center.

Referring to the accompanying drawings wherein the figures and letters of reference indicate like parts throughout the several views;

Figure 1 represents a plan view of the machine and sectional view of the bracket supporting the upper or stationary mandrel;

Figure 2 is a side elevation of the machine looking in the direction of arrow *a* of Figure 1 with the bracket for the stationary mandrel removed;

Figure 3 is an elevation of the machine looking in the direction of arrow *b* of Figure 1;

Figure 4 is a broken view of the upper surface of the machine bed, detail plan view of the link forming mandrel and its reciprocating carrier, and broken view of the actuating levers connected therewith;

Figure 5 is a broken view of the machine bed, detail view of the link forming mandrel and its carrier in its elevated position, broken view of the upper stationary mandrel, broken view of the cam for actuating the carrier, and broken view of the lever for actuating the wire gripping lever.

Figure 6 is a broken view of the machine

bed, broken view of the upper stationary mandrel, detail view of the movable mandrel and its operative elements in a re-treated position;

Figure 7 is an enlarged broken view of the several elements connected with the link forming mechanism in readiness to operate on an advanced section of the feed wire, the upper half of the mandrel not shown;

Figure 8 is an enlarged broken view of the link bending tools advanced to give the initial bend to the link about the mandrel, and the link carrying jaws holding a previously formed link in position to receive the link in process of forming, the upper half of the mandrel not shown;

Figure 9 is an enlarged view of the link closers in their advanced position engaging a link, broken view of one of the link closer slides, and broken view of the wire gripping lever, the upper half of the mandrel not shown;

Figure 10 is an enlarged broken view of the link carrying jaws and arbor for same, broken view of the upper and lower parts of the mandrel showing the jaws engaging a recently formed link;

Figure 11 is an enlarged broken view of the mandrel showing the lower half re-treated and the jaws detaching a recently formed link from the stationary half of the mandrel;

Figure 12 is an enlarged broken view of the link carrying jaws, broken view of their arbor, and broken view of the link gripping lever;

Figure 13 is a central sectional view of the housing in which is located the pivotally supported frame carrying the arbor, broken view of the arbor, and broken view of the segment lever for rotating the arbor, and

Figure 14 is a detail view of a chain section of short links.

1 represents the machine bed, 3 is the driving shaft journaled in the hangers 4, Figure 2 of the bed and carrying the driving pulley 5. The pinion 6 on said shaft meshes with the large gear 7 on the cam shaft 8, Figure 1, journaled in the bearings 9, 10, and 11 are cam shafts journaled respectively in bearings projecting from the bed, three of which, 13, 14, and 15 only being shown. The shafts 10 and 11 are driven from shaft 8 by the bevel gears 16, 17, 18, and 19.

110

The link carrying jaws 20, Figure 12, are pivotally supported on the pins 21 located near the inner end of the arbor 22 and are actuated to close upon a link by the spring 23. The arbor 22 is operatively mounted in the box 24, Figure 13, located within the stationary housing 25, and is pivotally supported therein by the screws 26, Figures 2 and 3. Teeth 27, Figure 13, are provided in the body of the arbor 22 meshing with the toothed segment lever 28, see also Figures 1, 2, and 3, journaled on the pin 29 of the standard 30. The lever 31 is pivotally connected to the segment lever by the pin 32, and the opposite end of lever 31 is journaled on the short shaft 33, Figures 2 and 3, which shaft is journaled in the standard 34 supported from the machine bed. 35 is a gear secured to the short shaft 33 meshing with the gear 36 mounted on the cam shaft 10 whereby shaft 33 is rotated. The oscillation of the segment lever 28 is effected through the medium of the cam groove 37 in the face of the gear 35 and the roll 38 carried by the lever 31.

The jaw carrying arbor 22 has a longitudinally reciprocating movement in the box 24 by means of the cam 39, Figure 1, on the shaft 10, and the lever 40 engages said cam 39 and the grooved collar 41 mounted on the outer end of the arbor.

The mandrel about which links are formed is divided into the two parts 42, 43, Figures 3, 5, and 6. The upper half 42 is adjustably located in the overhanging bracket 44 mounted on the housing 25, and the lower half is adjustably located in the carrier 45 mounted in the machine bed. This carrier is reciprocally operated by means of the cam 46, see also Figure 1, and the lever 47. The outer end of this lever carries the roll 48 operating in the cam groove 49 of the cam 46 and the inner end, Figures 3 and 5, is pivoted on the screw 50 attached to the carrier 45.

45 The wire gripping lever 51, Figures 5 and 6, is provided on the pin 52 of the carrier and has the grooved faced block 53 adapted to grip the wire in the manner presently to be described. The block 53 may, if desired, 50 form an integral part of the lever 51.

55 54, Figure 3, is a rock shaft journaled in the standard 55 carrying the arms 56, 57, see also Figure 1. The former of these arms is pivotally connected with the wire gripping lever 51 through the medium of the link 58. The rock shaft is oscillated to actuate the lever 51 by means of the arm 57 whose roll 59 operates in the groove 60 of the cam 61 mounted on the shaft 8.

60 62, Figure 1, is a slide mounted on the machine bed whose outer forked end carries the roll 63 engaging the cam 64 to force the slide towards the mandrel, while the roll 64 of said slide, operating in the cam groove

65, formed in the vertical face of the gear 65 7, serves to return the slide.

66, 67, Figure 1, are the tools adapted to give the initial bend to a link and are secured to the slide 62 by the screws 68, and are adjusted thereon by the set screws 69. 70 The bushing 70 is mounted in the housing 71 to serve as a guide for the feed wire 72, and the stop 73 is adjustably secured to the machine bed to serve as a stop for the wire.

75 74, 75, Figure 1, are the link closers adjustably secured to the levers 76, 77, which levers are pivotally supported by screws 78, 79, on the slides 80, 81, let into the upper surface of the machine bed. These slides carry at their outer ends the rolls 82, 83, engaging, respectively, the cams 84, 85, mounted on the shafts 10, 11, to effect an inward movement of the slides, and a return movement by means of rolls 86, 87, on the outer ends of said slides operatively engaging 85 cam grooves 88, 89, located respectively in the face of the cams 84, 85.

80 The blocks 90, 91, Figures 1 and 9, are adjustably secured to the upper surface of the machine bed and carry the rolls 92, 93, 90 adapted to engage with the curved edges 76^a, 77^a, of the levers 76, 77, and tilt the levers as the slides 80, 81 are moving inward to close a link.

95 The arbor carrying box 24, Figures 2, 3, and 13, is tilted on its pivotal screws 26 through the medium of the cam 94 on shaft 11, and levers 95, 96. The inner end of lever 95 is pivotally connected to the link 97 depending from the box 24, and its outer end 100 96 is connected to the short shaft 98 journaled in the bracket 99 secured to the underside of the bed 1. The inner end of lever 96 is also operatively connected with shaft 98 and its outer end carries the roll 100, Figures 105 1 and 3, operating in the cam groove 101.

110 It will be observed that the reduced inner ends 42^a, 43^a, of the mandrel 42, 43, Figure 6, about which the links are formed represents one half of a circle equal to the diameter of the wire so that, when the mandrel is closed, a curve is formed embracing one half of the inner curved surface of the wire. This arrangement preserves the round shape 115 of the wire, which would not be the case if only one part of the mandrel was employed and the link forming end or seat was lengthened the full diameter of the wire.

120 While I show the link sections severed from a feed wire, it will be readily understood that the link sections could first be cut to the proper length and delivered to the bending tools by any of the old and well known feeding methods.

125 The operation for automatically forming a link and interlocking it into a previously formed link to form a chain, is as follows:—

All of the operative tools being in neutral

or open position, the wire 72, Figure 7, is advanced against the stop 73, and the wire gripping lever 51 is then advanced to engage its block 53 with the projecting end 72^a of the wire and hold the same firmly against the closed mandrels 42, 43, Figures 1 and 5. The arbor 22 is advanced to place the previously formed link A, within the jaws 20, against the closed mandrels, Figure 8, when the bending tools 66, 67, are advanced to give the initial bend to the link, the former severing a link section as it passes across the inner end of the bushing 70.

While the tools 51, 66, 67, are in the position shown in Figure 8, the slides 80, 81, Figure 9, are inwardly advanced and the levers 76, 77, are tilted by the contact of their curved edges 76^a, 77^a, with the rolls 92, 93, to bring the link closers in position to engage the projecting ends *c*, *d*, of the partially formed link and close such ends within the previously formed link A while the said slides are moving inwardly.

As soon as a link has been closed in the manner above described, the tools 51, 66, 77, will retreat, Figures 6 and 7, and the jaw carrying arbor will retreat to disengage the jaws from the newly formed link B and make a quarter turn and also be given an upward tilt by means of the cam 94, Figure 1, and again advanced to grasp the link B, Figure 10. When the jaws are thus engaged, the lower half 43 of the mandrel will retreat, Figure 11, and the jaw carrying arbor will be given a downward tilt to strip the link B from the upper half 42 of the mandrel. When the link B has been cleared from the upper half of the mandrel, the arbor 22 will retreat with said link and reverse the previous quarter turn while the mandrel is closing and the tools 51, 66, 67, are again advanced into operative position for forming a new link, when the jaw carrying arbor will advance to place the link, within the jaws, against the former to continue the operation of chain making.

While the machine, above described, is capable of making links of any desired length, it is particularly adapted to make very short links. In other words, links wherein the diameters of the wire of two interlocking links practically fill the central opening of a companion link, as shown in Figure 14. Where there is plenty of spare room in this central opening, the new link is usually closed at the center of said opening, but with short links, as shown in Figure 14, the new link must be closed away from the center and at such a distance therefrom as will give the two interlocking links B and C the necessary freedom. It is for this purpose that the jaw carrying arbor is vertically tilted in order to carry a recently closed link from a higher plane to a lower one where the link

interlocking can be done at one side of the center of a previously formed link.

Having thus described my invention what I claim is:—

1. A wire chain making machine comprising a two part mandrel having seats at the adjacent ends of the two parts about which links are formed when the mandrel is closed, means for holding one part of the mandrel stationary, and means for actuating the other part to and from the stationary part, initial link bending tools, an arbor, means for oscillating it, and means for longitudinally actuating said arbor to and from the mandrel, said arbor carrying link holding jaws, and means for closing a partially formed link within a closed link held by the jaws and at one side of the center of said closed link.

2. A wire chain making machine comprising an arbor, a support therefor, means for oscillating and longitudinally reciprocating said arbor in its support, means for reciprocally tilting said support, a two part mandrel, means for separating and closing the mandrel, reciprocating initial link bending tools, reciprocating link closing tools for interlocking a partially formed link within a previously formed link held by the jaws and at one side of the center of said previously formed link, said arbor retreated as said links are interlocked so as to release the jaws from the previously formed link, and partially rotate and advance to engage the jaws with the newly formed link and detach said link from the two part mandrel, and again retreat and reverse its previous partial rotation and advance the newly formed link to the closed mandrel.

3. In a chain making machine of the character described, comprising a two part mandrel, one part held stationary and the other part movable to and from the stationary part, the adjacent ends of the two parts having seats about which links are formed when the mandrel is closed, initial link bending tools, link closing tools, a jaw carrying arbor, means for actuating said arbor to detach a closed link from the stationary part of the mandrel and present it to the closed mandrel for the interlocking of a new link at one side of the previously formed link held by the jaws.

4. In a chain making machine of the character described, comprising a mandrel about which links are formed, initial bending tools, a jaw carrying arbor adapted to carry a closed link, reciprocating slides, levers pivotally supported thereon, link closing tools mounted on the levers, and means for tilting said levers toward the mandrel.

In testimony whereof I affix my signature.

ANDREW BERG.
